CLAIM

The ornamental design for a bed organizer with pressure holder, as shown and described.

DESCRIPTION

FIG. 1 is a top plan view of bed organizer with pressure holder showing my new design;

FIG. 2 is a front elevational view thereof;

FIG. 3 is a bottom plan view thereof;

FIG. 4 is a right side elevational view thereof, the left side elevational view being a mirror image thereof;

FIG. 5 is a rear elevational view thereof;

FIG. 6 is a top, front, and right side perspective view thereof; and,

FIG. 7 is a top, rear, and left side perspective view thereof.
